UNITED STATES PATENT OFFICE.

GEORGE W. MILLER, OF LOS ANGELES, CALIFORNIA.

VENDING-MACHINE.

1,072,758.

Specification of Letters Patent. Patented Sept. 9, 1913.

Application filed January 22, 1912. Serial No. 672,557.

To all whom it may concern:

Be it known that I, GEORGE W. MILLER, a citizen of the United States, residing at Los Angeles, in the county of Los Angeles and

5 State of California, have invented a new and useful Vending-Machine, of which the following is a specification.

My invention relates to improvements in vending machines and especially to that 10 class of machines which are provided with rotary delivery mechanism having a plurality of carriers adapted to register with a corresponding number of magazines.

The principal object of my invention is to 15 provide a machine capable of vending either material in bulk or in packages and having adjustable carriers for changing the volume of the vendable material without changing the operating mechanism.

20 Another object of my invention is to provide a vending machine having vertical removable magazines, so that they may be conveniently refilled.

A further object of my invention is to improve and simplify the details of construction and make operation of the machine 25 positive.

Other obvious objects will appear in the accompanying specification and be more 30 clearly defined in the claims.

In the drawings:—Figure 1 is a perspective of the vending machine embodying the principles of my invention. Fig. 2 is a fragmental sectional detail showing a modified form of delivery. Fig. 3 is a front elevation looking in the direction of the arrow 3 in Fig. 4, parts being broken away to show the details. Fig. 4 is a vertical section upon the line 4—4 of Fig. 3. Fig. 5 is a rear view 35 of one of the magazines showing the door, buttons and slot for insertion of a false bottom. Fig. 6 is a fragmental sectional detail upon an enlarged scale and taken on the line 6—6 of Fig. 3. Fig. 7 is a horizontal section on the line 7—7 of Fig. 4 showing the details of mounting one of the magazines. Fig. 8 is a fragmentary rear elevation showing the adjustable coin slot as seen looking in the direction indicated by the arrow 8 in 45 Fig. 4. Fig. 9 is an enlarged cross section of the coin mechanism taken on the line 9—9, in Figs. 3 and 10. Fig. 10 is a fragmentary sectional detail on the line 10—10 of Fig. 9.

55 Referring to the drawing in detail: My vending machine is mounted in a casing,

The back 1 is preferably formed of wood and the sides 3 and 4 are preferably formed of sheet metal secured rigidly to the back. The rigid front 5 is secured to the forward edge of the bottom 2 and the forward edges of the sides 3 and 4 and the front 5 extending upwardly as high as the driving shaft 6. The front 5 is formed preferably of sheet metal and has a delivery opening 7 extending from the bottom 2 upwardly. The remaining portion of the casing comprising the sides 8 and 9, the top 10 and the swinging front 11 preferably formed of sheet metal in the shape of a cap and secured to the upper edge of the front 5 by hinges 12. The sides 8 and 9 match the sides 3 and 4 and the lower edge of the front 11 meets the upper edge of the front 5.

The magazines 13 are provided with glass panels in front sides thereof and the front 11 of the casing is provided with like panels of glass, which permits a view of the contents of the magazines and reveals to the operator the amount of commodity in said 75 magazines. The machine as shown has two removable magazines substantially alike. The number of magazines may be increased as desired. When two magazines are used, delivery is made alternately and when more 80 than two magazines are used delivery is made successively. When only a single magazine is used the wheel 31 and drum 24 are rotated a full revolution for each delivery but when two magazines are used the 85 wheel and drum make only one-half of a revolution for a delivery, and so on. Brackets 14 extend rigidly forwardly from the back 1 there being a bracket at the lower end and a bracket at the upper end of each magazine. Spring clips 15 extend forwardly from the brackets and the magazines 13 are formed of sheet metal rectangular in cross section and meet between the clips 15, there being handles 16 upon the forward ends of 90 the clips for spreading the clips and releasing the magazines. Each magazine is provided with an opening 17 in its rear side and this opening is provided with a door 18 swinging upon hinges and held closed by 95 buttons 19. Said magazines are provided with slots 19^a in the lower ends thereof for the reception of a false bottom 19^b, as shown in Fig. 5 so that when the magazines are to be refilled this false bottom may be inserted 100 and when the magazines are replaced it may be withdrawn and kept in any convenient 105

place within the casing. Lugs 20 project from the sides of the magazine above and below the clips 15 to hold the magazines in their desired horizontal planes. Flanges 21 and 22 extend forwardly and backwardly from the lower ends of the sides of the magazines. Bearings 23 are secured to the inner faces and at the upper edges of the sides 3 and 4 and the shaft 6 is mounted in these 10 bearings. A sheet metal drum 24 is mounted upon the shaft 6 for carrying the adjustable delivery mechanism. Pockets 25 and 26 are formed in the sheet metal drum 24 one at each end of the drum and diametrically opposite each other, said pockets registering with the magazines 13, when the drum is in normal or locked position. An adjustable bottom 26^a is mounted in each pocket upon adjusting screws 27, screw seated 20 through the bottom of the pockets so that by manipulating the adjusting screws 27, the bottom 26^a may be raised or lowered to increase or decrease the volume of commodity which the carrier will receive. The pockets 25 and 26 in the delivery drum 24 are larger than the ends of the magazine 13, so that in operation the pockets need not exactly register with the magazines before the package is dropped and so as to allow time for the 30 package to drop without wedging. The entrances to the pockets are rounded on their forward and backward edges to form cam faces 27^b, so as to prevent jamming in moving the package in the pocket from under 35 the other packages in the magazine. This construction facilitates the cutting off of material in bulk. An opening 27^c is formed in one end of the drum 24 so that the screws 27 may be reached for adjustment without 40 dismantling the machine.

A guide plate 28 extends from the flange 21 forwardly and downwardly concentric to the shaft 6 and then forwardly to the upper edge of the opening 7 and a second guide 45 plate 29 extends from under the periphery of the drum 24 to the lower edge of the opening 7, said plate extending from the sides of the partition downwardly at an angle, thereby forming a common delivery for 50 the magazines. Flanges 30 extend around the drum 24 on each side of each pocket 25 and 26 and fit closely against the sides of lower ends of magazines 13 to prevent particles of loose material from working out 55 and clogging movement of the drum 24 or getting into the interior mechanism of the machine. Partitions 30^a are inserted at each end of the drum 24 and extend upwardly to the parting line of casing and are joined at 60 their forward ends to front 5 thereby forming walls for the opening 7, which arrangement completes the inclosure of the inner mechanism of the machine.

The wheel 31 is fixed upon the shaft 6 for 65 controlling the drum 24. Notches 32 are

formed in the periphery of the wheel 31 and the spring actuated pawl 33 is pivoted in place to engage in notches 32. The spring pawl 34 engages the wheel 31 to hold it from rotating backwardly. The coin chute 70 35 is mounted vertically and leads from the coin slot 36 downwardly and backwardly in front of the wheel 31. A tooth 37 projects from the pawl 33 into the coin chute 35. The wheel 38 is mounted loosely upon the 75 shaft wheel and rigid with the handles 39. Arms 40 and 41 project from the wheel 38 diametrically opposite each other and lugs 42 project inwardly from the outer ends of the arms so as to pass through the concentric 80 slot 43 formed in one end of the coin chute 35. As the coin 44 is inserted through the coin slot 36 it passes downwardly in the coin chute 35 until it strikes the arm 37 of the pawl 33, then if the handle 39 is operated 85 one of the lugs 42 will press downwardly upon the coin 44 thereby swinging the arm 37 downwardly and swinging the pawl 33 out of engagement with notches 32 and allowing the delivery mechanism to operate. 90

The lugs 45 and 46 extend outwardly from the wheel 38. Similar lugs 47 and 48 extend outwardly from the face of the wheel 38 so as to form spaces for lost motion. The lugs 49 and 50 extend outwardly from the face of the wheel 31, the lug 49 being between the lugs 45 and 47 and the lug 50 being between the lugs 46 and 48, so that there is lost motion between the wheels 38 and 31 equal to the distance between the lugs 45 and 47 to 46 and 48. The coil spring 51 connects the wheel 38 to the shaft 6. The tension of the coil spring is exerted to rotate the wheel 38 forwardly until the lug 46 strikes the lug 49, or the lug 50 strikes the 100 lug 48. The plate 52 is adjustably secured against the inner face of the front 11 by clamps 53, said plate covering a part of the coin slot 36 so that by adjusting the position of the plate the coin slot may be adjusted to meet the desired coin. 110

Either loose material in bulk, such as peanuts, or packages or tablets, such as candy, may be placed in the removable magazines 13. The delivery mechanism may be adjusted to suit the material to be vended by operating the adjusting screw 27 to locate the adjustable bottom 26^a. The coin slot 36 may be adjusted to suit the desired coins, such for example as a dime, a nickel or a penny, and when the coin is inserted and the handle 39 operated the material will be delivered under the guide plate 29. 115

A door 54 is pivotally mounted in the opening 7 for closing the lower part of the opening so as to catch loose material. When the delivery mechanism discharges upon the guide plate 27 the material falls against the inner side of the door 54 and then the door 120 may be opened and the material removed. 130

Or if a package the same may be removed without disturbing the door 54.

The operation of the modification shown in Fig. 2 is identical with that of the machine in the other views, with the exception that the guide plate 28 extends downwardly to a point near the vertical center of the machine thereby holding the contents of the pocket until the drum has been operated to bring said pocket to a position as shown in Fig. 2. The bottom 2 in this view is shown at an angle so that packages or bulk material when delivered will slide outwardly to the hinge door 54, and may be conveniently reached by the purchaser.

I desire to call especial attention to the fact that I have produced a vending machine having adjustable delivery mechanism adapted for handling either loose material or packages and having removable magazines, and having an adjustable coin mechanism so that the machines may be manufactured without regard to the specific material to be handled or the specific coins to be used and each individual machine may be readily adjusted to the desired material and to the desired coins.

The details of construction may be carried out in many ways without departing from the spirit of my invention as set up in the following claims.

I claim:—

1. In a vending machine, a casing, a shaft journaled in said casing, a delivery drum mounted upon said shaft and having adjustable delivery pockets therein, a plurality of removable magazines mounted in said casing, annular flanges extending around said delivery drum and adapted to inclose the lower ends of said magazines, and outwardly extending lips upon the lower ends of said magazines to prevent material to be vended from dropping through, into the operating mechanism, and locking pawls mounted upon the frame to prevent rotation of the drum between operations.

2. In a vending machine, the combination of a casing, a shaft journaled in the casing, a delivery drum mounted upon said shaft, and having adjustable delivery pockets therein, a plurality of removable magazines mounted in the casing in alinement with said pockets, annular flanges extending around said drum and adapted to close the sides of said magazines, outwardly extend-

ing lips upon the lower ends of said magazines, guards extending upwardly from the front of said casing to said lips and covering said drum, so that when the drum is rotated to deliver material to the purchaser, it will be held in said pockets upon continued rotation of the delivery drum.

3. In a vending machine, a bottom; a back wall extending upwardly from the bottom the height of the machine; rigid sides extending upwardly a short distance; a rigid front extending upwardly the height of the rigid sides; a swinging front, sides and top fixed together and hinged to the rigid front so as to fit the back and form a casing; a shaft mounted at the parting line between the rigid sides and the swinging sides; a cylindrical drum mounted upon the shaft; and a removable magazine mounted above the drum, there being a delivery pocket in the drum adapted to register with the magazine; and a guard extending from the lower edge of the front wall of the magazine to the delivery opening, said delivery opening being in the rigid front, so as to hold the material in the pocket as it is carried from the bottom of the magazine to the delivery opening.

4. In a vending machine, a bottom; a back wall extending upwardly from the bottom the height of the machine; rigid sides extending upwardly a short distance; a rigid front extending upwardly the height of the rigid sides; a swinging front, sides and top fixed together and hinged to the rigid front so as to fit the back and form a casing; a shaft mounted at the parting line between the rigid sides and the swinging sides; a cylindrical drum mounted upon the shaft; a removable magazine mounted above the drum, there being a delivery pocket in the drum adapted to register with the magazine; a guard extending from the lower edge of the front wall of the magazine to the delivery opening, said delivery opening being in the rigid front; a guide plate extending from under the periphery of the drum to the lower side of the delivery opening; and partitions extending from the guard to the guide plate.

GEORGE W. MILLER.
